Patented June 22, 1920.

FIG. of 1.

FIG. of 2.

FIG. of 5.

FIG. of 6

Matteo Tamburini,
John Stewart
ATTORNEY

UNITED STATES PATENT OFFICE.

MATTEO TAMBURINI, OF PATERSON, NEW JERSEY.

LOOM-CLOCK.

1,343,988.

Specification of Letters Patent. Patented June 22, 1920.

Application filed July 19, 1919. Serial No. 312,027.

To all whom it may concern:

Be it known that I, MATTEO TAMBURINI, a citizen of the United States, residing at Paterson, in the county of Passaic and State 5 of New Jersey, have invented certain new and useful Improvements in Loom-Clocks, of which the following is a specification.

This invention relates to so-called "clocks" for looms and the like machines, and 10 especially looms, its object being to provide a clock which may be readily attached to any loom and which will be so constructed that it will register accurately at all times and be proof against being tampered with 15 by unauthorized persons.

In the accompanying drawing,

Figures 1 and 2 are side and front elevations, respectively, showing my clock applied to a loom frame; 20 Fig. 3 is a front elevation of the clock, partly broken away, a part of the loom frame being also shown in section;

Fig. 4 is a front elevation, partly in section, of a part of the transmitting train 25 without the housing shown in Fig. 3;

Fig. 5 is a plan of the clock; and

Fig. 6 is a horizontal sectional view on the line 6—6 in Fig. 3 and illustrating a modification.

30 *a* is the frame and *b* the sand roll of a loom, the latter being suitably rotated by the gearing *c*. The shaft *d* of the sand roll may have a collar *e* (Fig. 3) suitably secured thereon, the collar having an interior knurled 35 bushing *f* or (Fig. 6) the knurled bushing *g* may be set directly in the end of the shaft.

Detachably secured to the side of the loom frame is a support *h*, in the present case being a rectangular elongated block of wood 40 standing upright and having a cavity *i* at its lower end and a bore *j* extending from the cavity clear to the top. The support thus forms a housing. The cavity *i* may be provided with a lockable door *k*. At the top of the 45 housing *h* the dial and pointer are arranged. Of course either of these elements may be the movable one, but I prefer to have the dial fixed and form it on an annulus *l* which is countersunk into the top of the 50 housing. The pointer will be referred to later, its rotation being effected by the following transmission train:

In a U-shaped yoke *m* fixed within the cavity *i* is horizontally journaled a worm *n* whose stem protrudes from the housing and 55 has its end formed as a knurled boss *o* adapted to form a coupling with the knurled bushing *f* or *g*, as shown. Secured in the cavity by the screw *p* is a rotary worm wheel *q* rotatable on a vertical axis and having a depending hub *r* journaled in the step-bearing *s*, and also having an upstanding hub *t* having an internally knurled socket *u*. A shaft *v* having a reduced knurled lower end *w* is coupled with the worm-wheel *q* by 60 having its knurled portion fitted into the knurled interior of the hub *t*, said shaft being capable of being rotated independently of the worm-wheel by elevating it (as by reaching into the cavity upon opening the 65 door *k*) clear of the worm-wheel. The shaft has a bearing at its upper end in a sleeve *x* fitted into the upper end of the bore *j*. The head *y* of the member constituted by the shaft *v* includes a disk *z* on which the 70 pointer 2 is provided, a knurled knob or handle 3 projecting upwardly, and a shank 4 projecting downwardly, the shank fitting a socket in the upper end of the shaft and having a radial pin 6 entering a slot 7 in the 75 shaft.

It will be understood that when the loom is operating the sand roll will rotate the transmission train and the yardage woven will be indicated by the pointer 2 with reference to the dial 1. When it is desired to reset the pointer to zero, the operator opens the door *k* and upon elevating the shaft or member *v* to break the coupling between such member and the neighboring member 80 *q* in the train turns said shaft until pointer 2 registers with zero. If an unauthorized person should attempt to disturb the calculation by elevating and turning the head *y* of member *v*, the attempt would be abortive 85 because such manipulation would withdraw pin 6 from slot 7 and so uncouple said head from the shaft; if the head is so disturbed, the weaver has only to turn the same until the pin again enters the slot 7, which will of 90 course leave the pointer to register the same as before the mechanism was tampered with.

Having thus fully described my inven-

tion, what I claim as new and desire to secure by Letters Patent is:—

In combination, a housing and means therein to measure the progress of a moving element including a transmission train having an upright rotary member normally coupled at its lower end and within the housing with a neighboring member in the train but

movable upwardly to disestablish the coupling, said member having an upwardly detachable head normally connected to turn therewith and protruding upwardly from the housing, said head and the top of the housing having a coacting pointer and dial. 10

In testimony whereof I affix my signature. 15
MATTEO TAMBURINI.
